UNITED STATES PATENT OFFICE.

VANNEVAR BUSH, OF MEDFORD, MASSACHUSETTS, ASSIGNOR, BY MESNE ASSIGNMENTS, TO RAYTHEON MANUFACTURING COMPANY, OF CAMBRIDGE, MASSACHUSETTS, A CORPORATION OF MASSACHUSETTS.

ELECTRICAL APPARATUS.

Application filed April 7, 1922. Serial No. 550,519.

The present invention relates to electrical apparatus and more particularly to apparatus of the type disclosed in the copending application of Bush, Serial No. 510,916, filed October 27, 1921, and Smith, Serial No. 526,095, filed December 31, 1921.

These applications relate to electrical apparatus having cooperating electrodes immersed in a gas and so designed and located with respect to one another that the conductivity of the gas filled space separating the electrodes may be controlled.

The object of the present invention is to improve the construction and operation of this type of apparatus and to this end one feature of the invention contemplates the provision of closely spaced carbon electrodes immersed in a gas, one of the electrodes having an opening communicating with a hollow space behind the surface of sufficient size to permit formation of a space charge.

A further feature of the invention contemplates the provision of a hollow carbon electrode provided with an oxide coating upon its active surface to decrease the voltage drop between the electrodes and increase the capacity of the tube embodying these electrodes.

In a simple form of the invention an oxide of calcium, barium, strontium, or mixtures of these oxides, is applied to the surface of the electrode with rosin and the coated electrode is then heated sufficiently to bind the mixture of oxide and rosin thereon.

Still further features of the invention consist in certain novel features of construction, combinations and arrangements of parts hereinafter described and claimed, the advantages of which will be obvious to those skilled in the art from the following description.

The accompanying drawing illustrates a section in elevation of a tube embodying the features of the present invention.

Fig. 1 is a vertical sectional view of the discharge device.

Fig. 2 is a top plan view of the cathode, and

Fig. 3 is a cross sectional view through the stem.

The illustrated embodiment of the invention shown in the drawing comprises a hermetically sealed receptacle 10 filled with helium or other suitable gas and having co-

operating electrodes indicated generally at 55 12 and 14 immersed therein. The electrode 12 comprises a carbon disk 16 having an opening 18 formed centrally therein surrounded by a tubular neck 20. The opening 18 communicates with a chamber or space 60 enclosed by a carbon cup 22 which engages with the surface of the disk 16, as indicated, and forms in combination with the disk a hollow electrode with an opening extending into the interior. The carbon disk 16 65 is positioned by a series of supports 24 having shoulders 26 formed thereon, the supports being connected with rods which extend upwardly beyond the cup 22 and are connected above the cup by wire or similar material to hold the cup and disk in assembled relation, as clearly shown in the drawing. Cooperating with the hollow electrode is the electrode 14 consisting of an imperforate disk of carbon positioned in 70 close proximity to the surface of the carbon disk 16, as indicated. The solid or imperforate disk 14 is conveniently maintained in operative position by a tubular support 26 75 which extends upwardly within the support 80 for the cooperating electrode.

The supporting members for the two electrodes may be conveniently connected to the tube in the same manner as disclosed in the application to Smith, Serial No. 526,095, 85 hereinbefore referred to.

Such a tube will conduct current freely when the hollow electrode is negative and will insulate against such conduction when the opposite or solid electrode is negative. 90 This is believed to be due to the formation of a space charge in the space enclosed by the hollow electrode, as explained in the Smith application above referred to, all paths available for conduction through the gas, except paths through the opening in the hollow electrode, being too short to permit ionization and conduction. In the illustrated embodiment of the invention the electrodes have opposing surfaces separated a distance comparable to the mean free path of electrons in the gas. The provision of an oxide coated carbon cathode in a tube of this character decreases the voltage drop through the tube and increases the current carrying capacity. This oxide coating may take the form of an oxide of calcium, barium or strontium, or mixtures of these oxides, mixed 100 105

with a rosin binder and burned onto the surface of the electrode, forming a surface coating which functions as the active surface of the cathode. With a typical tube of this construction it has been found possible to pass two-tenths of an ampere with a voltage drop through the tube of one hundred twenty-five to one hundred fifty volts approximately.

- 10 The tube as illustrated is conveniently embodied in a simple form of rectifying circuit consisting of a source of alternating current initially indicated at 50 and included in a primary circuit 52 which is inductively 15 coupled to a secondary circuit 56 including the rectifying tube.

From the foregoing it will be evident that the lower end of the cathode constitutes an obstruction having a restricted opening for 20 electrical discharge between the active cathode surface and the anode surface and that the space adjacent the active cathode surface (the interior of the hollow cathode) is isolated from the space adjacent the anode 25 surface except through the aforesaid restricted opening; also that the interior surface of the hollow cathode has, by virtue of the aforesaid coating, a lower work function than the exterior surface and that, 30 owing to the location of the anode adjacent the opening in the hollow cathode, the electrical discharge is confined to that surface of the cathode having the low work function.

- 35 The interior surface of the cathode 22, which constitutes the active cathode surface, and the upper surface of the anode 14, are obviously separated from each other by the obstruction comprising disk 16 which forms 40 a cover for the lower end of the cathode, the upper end of the cathode being closed by a cover integral with the peripheral wall of the cathode. Consequently the space adjacent the interior active surface of the cathode 45 is isolated from the anode except that portion of the anode presented to the active cathode surface through the restricted opening in the cover 16.

In a generic sense the term hollow cathode 50 includes a cathode whose active surface only partially surrounds a gaseous medium so that the medium immediately adjacent the active surface is more or less pocketed or confined.

- 55 From the foregoing it will be evident that the tube 24, which defines a long narrow space between this tube and the tube 26, constitutes means for substantially preventing particles of the coating on the inside 60 of the hollow cathode which are dislodged from the cathode during operation from reaching the wall of the tube 10.

From the foregoing it will be evident that 65 the present invention is particularly applicable to gaseous conduction tubes of the type

in which the cathode functions below the temperature at which rectification is dependent upon thermionic emission, as form an incandescent surface, since in these so-called thermionic tubes the potential drop 70 is low and the cathode is not subjected to intense ion bombardment.

I claim:

1. A gaseous conduction device comprising a sealed tube containing an obstruction 75 having a restricted opening therethrough and an active cathode surface on one side of said obstruction, and an anode presented to said active cathode surface through said opening from the other side of the obstruction, said cathode surface comprising material having a low work function to increase electron emission and the space adjacent the cathode surface being substantially isolated except through said restricted opening so that any of said material which is liberated during operation is substantially restricted to the region of gaseous conduction. 85

2. A gaseous conduction device comprising a hollow cathode with an opening therein and an anode presented to the interior surface of the hollow cathode through said opening, said surface having a substantially lower work function than the exterior surface of the cathode, and means for keeping 95 said work function lower during operation of the tube.

3. A gaseous conduction device comprising a hollow cathode with a restricted opening and an anode presented to the interior surface of the hollow cathode through said opening, said surface having a substantially lower work function than the exterior surface of the cathode, and means for keeping 100 said work function lower during operation of the tube, said means providing a gap substantially confined to the mean free path of electron in the gas.

4. A gaseous conduction rectifier employing an arrangement of electrodes including a cathode which functions below the temperature at which rectification is dependent upon thermionic emission, the cathode being hollow and having an interior surface comprising material which affords a low work function and which is partially liberated during operation, and means for restraining 110 liberated material from escaping from the region of said surface.

5. A gaseous conduction tube comprising an anode, a cathode surface presented to said anode, said surface being coated with material which adheres when cold but is partially liberated during operation and which largely increases the electron emission, and means for substantially preventing the liberated material from reaching the wall of the tube. 125

6. Gaseous conduction apparatus compris- 130

ing an anode, a hollow cathode having an interior surface presented to said anode, said surface comprising material which is liberated during operation and which largely increases the electron emission, and means to restrict the escape of said material when liberated.

7. A gaseous conduction tube comprising a hollow cathode with a restricted opening

and an anode presented to the interior surface of the hollow cathode through said opening, said surface having a substantially lower work function than the exterior surface of the cathode, and means for substantially preventing particles which are dislodged from said surface during operation from reaching the wall of the tube.

VANNEVAR BUSH.
